A. C. Barstow's Design for Partition Stove

Patented June 3, 1862.

A. G. Barstow, of Providence, R. I.
Letters Patent No. 1600, dated June 3, 1862.

The schedule referred to in these Letters Patent and making part of the same.

To all persons to whom these presents shall come:

Be it known that I, A. G. Barstow, of Providence, in the County of Providence, and State of Rhode Island, have invented a new and original design for Base and Front for Parlor Stove, and I do hereby declare that the following description, taken in connection with the accompanying drawings, to which reference is hereinafter made, is a full and exact specification of the said design.

The figures of the accompanying plate of drawings represent my new design.

Fig. 1. is a plan or top view of the base plate E.

Fig. 2. is an elevation or front view of the base plate and front plate in connection.

Fig. 3. is a vertical transverse section of the base plate on the line C-D.

Fig. 4. is a transverse horizontal section of front plate on the line A-B.

E, E, in the drawings Fig. 2. represents the bottom or base plate of the general form and curved outline shown in Figs. 1 and 3. Upon this bottom plate rests the superstructure, of the general form and outline shown in Figs. 4 and 2, ornamented with the several bands f, g, and k, and with the raised figures a, b, c, d, e, applied to the exterior face of said front plate and the sliding doors therein as fully shown on the annexed drawings.

Having thus fully described my new design I shall state my claim as follows.

What I claim as my invention and desire to have secured to me by Letters Patent, is the new design for Base and Front for Parlor Stoves, having the general ornamental form and configurations as herein above described and represented in the drawings.

Witnesses,

Geo. Gilbert Richmond,

William F. Elliot.
